UNITED STATES PATENT OFFICE

154,574

DESIGN FOR A DOUGH MOLDING MACHINE

Robert N. Winfree, Lynchburg, Va.

Application June 9, 1947, Serial No. 139,547

Term of patent 14 years

(Cl. D55—1)

To all whom it may concern:

Be it known that I, Robert N. Winfree, a citizen of the United States, residing at Lynchburg, in the county of Campbell and State of Virginia, have invented a new, original, and ornamental Design for a Dough Molding Machine, of which the following is a specification, reference being had to the accompanying drawings, forming part thereof.

Figure 1 is an elevational view of one side, Fig. 2 is a top plan view, Fig. 3 is an elevational view of the other side, and Fig. 4 is an end elevation, of a dough molding machine, showing my new design.

The dominant features of my design reside in the portion shown in full lines.

I claim:

The ornamental design for a dough molding machine, as shown and described.

ROBERT N. WINFREE.
